UNITED STATES PATENT OFFICE.

ELFON P. WOKEN, OF NORTHWOOD, NORTH DAKOTA.

FLASH-ABSORBER FOR MACHINE-GUNS.

1,339,614.

Specification of Letters Patent. Patented May 11, 1920.

Application filed March 6, 1920. Serial No. 363,784.

To all whom it may concern:

Be it known that I, ELFON P. WOKEN, a citizen of the United States, residing at Northwood, in the county of Grand Forks, 5 State of North Dakota, have invented certain new and useful Improvements in Flash-Absorbers for Machine-Guns; and I do hereby declare the following to be a full, clear, and exact description of the invention, such as will enable others skilled in the art to which it appertains to make and use the same.

This invention relates to machine guns, and more especially to devices for hiding the 15 flash and suppressing the smoke therefrom so as to prevent the enemy from locating the position of the firing piece.

The object of the invention is to produce an attachment for application to machine 20 guns as now in common use, which contains means for mechanically arresting the sparks and flames which are driven from the barrel, means for extinguishing them by water spray or steam taken from the reservoir or 25 jacket, and means for inclosing the entire mechanism within a hood for hiding or concealing the illumination completely.

The invention also includes details of construction whereby this general idea may be 30 carried out, and it is described herein as for application to the Browning machine gun, although of course it could be applied to guns of other make.

In the drawings:

35 Figure 1 is a side elevation and Fig. 2 a longitudinal section showing the front end of the machine gun with this attachment applied.

Fig. 3 is a front elevation and Fig. 4 a 40 rear elevation of the attachment on a larger scale.

With respect to the machine gun, we are concerned only with the reservoir or jacket J surrounding the barrel B for cooling, and 45 the letter S designates the front sight. The barrel as herein shown extends through the jacket near the lower part of the latter and out at its front end.

The numeral 1 designates a hood which 50 may be of sheet material and of any appropriate size and shape, but by preference it is circular at its rear end where it is provided with a flange 2 having perforations 3 through which may be passed screws 4 or 55 other fastening devices for holding the flange on the front end of the jacket J.

Otherwise the hood is of any appropriate or desired shape and design, but preferably it curves downward as at 5 to what might be called a nose 6 which has an opening 7 directly alined with the axis of the barrel, and an inturned flange 8 around said opening. Through the latter are projected the bullets as indicated in dotted lines, and the flange catches and throws back to the rear the 65 sparks and burning gases ejected from the barrel and which would otherwise be visible.

Pivots mounted through an opening at an appropriate point in the flange 2 is a gate or valve 9 which may be moved to close the 70 barrel-opening through the front end of the jacket when the barrel has become choked and has to be withdrawn for cleaning or repair, but ordinarily this gate stands open as seen in Fig. 4.

Tapped through the wall of the jacket near its top at the point 10 is a small pipe 11 which is led over the flange and preferably inward through the wall of the hood as seen in Fig. 2, wherein it is branched as 80 at 12, carried downward as at 13, supported by a clip 14 attached to said wall, and the lower ends of the branches directed inward over the upper flange 8 in small nozzles 15. By this means water spray or vapor, or 85 steam when it is generated within the jacket, is continuously fed downward and directed in jets rearward within the hood along the line of fire from the barrel through the opening 7. The hotter the gun gets under the 90 stress of action, the more steam generated and therefore the stronger the jets. The latter of course extinguish the sparks and flames issuing from the barrel, so that no particles thereof pass through the opening 95 7. Therefore the flash is entirely absorbed, and the position of the gun is concealed from the enemy.

While the detailed construction herein shown is adapted for a certain make of machine gun, I desire it to be understood that the showing is only illustrative, and the invention is applicable to other makes; and the claims below are to be construed with this understanding.

100 What is claimed is:

1. The herein described flash absorber for guns, the same comprising a hood having a bullet-opening, means for supporting the hood with said opening forward of and 110 axially alined with the barrel, spark arresting devices within the hood around its open-

ing, and means within the hood for throwing a liquid jet onto the gases issuing from the barrel.

2. The herein described flash absorber for 5 guns, the same comprising a hood having a bullet-opening, means for supporting the hood with said opening forward of and axially alined with the barrel, a flange within the hood around its opening bent toward 10 the barrel, a pipe within the hood having a nozzle adjacent the flange also directed toward the barrel, and means for supplying liquid to said pipe.

3. The combination with a machine gun, 15 and a jacket surrounding its barrel; of a flash absorber including a hood secured to the jacket and having a bullet-opening in alinement with the barrel, a pipe carried by the hood and connected at one end with the 20 steam space of said jacket, and a nozzle at the other end of the pipe directed toward the gases issuing from the barrel.

4. The combination with a machine gun, 25 and a jacket surrounding its barrel; of a flash absorber including a hood secured to the jacket and having a bullet-opening in alinement with the barrel, a pipe connected at one end with the steam space of the jacket and led thence into the hood and branched, 30 and nozzles on its branches adjacent said bullet-opening and directed toward the barrel.

5. The combination with a machine gun including a barrel, and a water jacket inclosing and rising above the same; of a flash 35 absorber comprising a hood having a flanged rear end for attachment to the front end of said jacket and a bullet-opening in its front end alined with the barrel, its wall being turned rearwardly around said opening into 40 a flange, a pipe connected at one end with the steam space of the jacket and extending thence into the hood, and a nozzle at the other end of the pipe adjacent said flange.

6. The combination with a machine gun 45 including a barrel, and a water jacket inclosing and rising above the same; of a flash absorber comprising a hood having its rear end radially flanged for attachment to the front end of said jacket and its forward 50 end provided with a bullet opening in line with said barrel, said flange being cut away at one point adjacent the barrel, a gate mounted in said cut-away portion, nozzles within the hood directed toward the mouth 55 of the barrel, and pipes connecting them with the steam space of the jacket.

In testimony whereof I affix my signature in the presence of two witnesses.

ELFON P. WOKEN.
